UNITED STATES PATENT OFFICE

2,473,363

WIRE SUPPORTING DEVICE

John Brown Cook and Leonard L. Jugle, Chicago,
Ill., assignors to Reliable Electric Company,
Chicago, Ill., a corporation of Illinois

Application November 26, 1945, Serial No. 630,857

1 Claim. (Cl. 287—81)

1

This invention relates to an improved construction for a wire supporting device which is used in connection with power transmission and distribution lines.

In transmission line practice it is frequently desirable to support the wire from the supporting arm by so-called "dead end" practice. This means that the end of each span of wire is supported by a strain insulator assembly in the same manner as if it were a dead end wire. Such strain insulator assemblies are used in connection with the adjacent ends of adjoining spans, and instead of using a separate jumper to connect the adjacent spans, the continuity of the wire is not broken, but directly connects one span with the other.

Such dead end strain insulator assembly usually includes a wire supporting member around which the wire may be looped or snubbed, and by means of which the tensile stress is transferred from the wire to the strain insulator. Such a member is grooved in order that the wire may be retained in position.

Such wire supporting members in the past have often been castings.

When an aluminum transmission wire is used, it is desirable to provide an aluminum wire supporting member, but the aluminum castings previously used are objectionable due to their comparatively high cost.

It is an object of this invention to provide a wire supporting member fabricated from sheet material which may be manufactured at less cost than the cast aluminum fittings heretofore used.

It is a further object of this invention to provide a wire supporting member which is fabricated from two plates which are secured together, the construction being such that flexural stresses are virtually eliminated, and the tendency to buckle is greatly minimized. Thus, a construction is provided which is practical for a non-ferrous metal, such as aluminum.

That embodiment of the invention which is herein shown and described is often referred to as a thimble. When thimbles are used in dead end practice, the wire is secured to itself, in front of the thimble, by suitable connecting means. However, it is obvious that this invention is equally applicable to other types of wire supporting members, such as those referred to as snub type dead ends, in which the construction is such that the wire supporting member exerts a more marked snubbing action, and the free end of the wire is clamped to the snub type dead end, rather than to the span itself.

2

Other objects, features and advantages will become apparent as the description proceeds.

With reference now to the drawings, in which like reference numerals designate like parts—

5 Fig. 1 is an elevation of a transmission line supporting means embodying this invention;

Fig. 2 is an end view of one of the thimbles shown in Fig. 1;

Fig. 3 is an elevation of the thimble shown in 10 Fig. 2;

Fig. 4 is a right hand end view of the thimble of Fig. 3; and

Fig. 5 is a plan view of the thimble of Fig. 3.

With reference now to Fig. 1, the reference 15 numeral 11 designates the usual pole having cross arms 12. Insulators 13 are mounted on the cross arms by means of bolts 14, and the insulators also include supports 15 on which the thimbles 16 are mounted. It will be seen that

20 the wire 17, or other suitable conductor, is looped around the thimble 16, and then is secured to itself by means of split bolt connectors 18. By means of this construction, the stress of that portion of the wire 17 which forms the span 30

25 between adjacent poles, is uniformly divided between the two halves 31 and 32 of the loop. That portion of the wire 17 which connects span 30 with an adjacent span 33, and which is relieved of the stress of the two spans, is designated by 30 the reference numeral 34.

The thimble, as shown in Figs. 2 to 5, inclusive, comprises two plates 19 and 20, the central portions 21 and 22 of which are secured to each other by a plurality of rivets 26. The main portions 35 of plates 19 and 20 are of circular shape, and the marginal portions are offset to form offset edges 23 and 24. These offset edges cooperate to form a groove 25 which, in the embodiment shown, extends through an arc of 270 degrees, more or less. That side of the thimble which faces the span may be cut off, as shown in Fig. 3, to save material, inasmuch as it is necessary to provide a groove 25 which extends through an arc sufficiently long to provide only tangential contact 40 with the two halves of the loop of the wire 17.

The plates 19 and 20 are also provided with rearwardly extending supporting arms 27 and 28 which are apertured as indicated at 29 to provide a means by which the thimble 16 may be secured to the support 15 of the insulator 13.

In operation, it will be evident that the wire 17 is disposed in the arc shaped groove 25, the groove being of sufficient radius with respect to the diameter of the wire so that undue strains 50 are not imposed on the wire due to the bending

thereof. The V-shape of the bottom of the groove 25 provides a secure seat for the wire, and the tendency of the plates to separate, due to the force exerted by the wire on the bottom of the groove, is successfully resisted by disposing the rivets 26 closely adjacent the bottom of the groove. It will be noted that a whole series of rivets is thus provided so that the strain on any one rivet is not excessive.

In that embodiment of this invention which is shown herein, it will be seen that the central portions of the plates form a web which takes up the axially directed force exerted by the wire on the bottom of the groove. Thus, the groove itself is not subjected to the flexural stress which is present in the usual type thimble, and which tends to deform the groove portion. Any tendency of the separate plate portions to buckle is minimized by the disposition of the rivets closely adjacent the bottom of the groove, and the provision of a plurality of rivets spaced at substantially 30 degree intervals.

The use of the construction herein shown permits manufacture of a thimble from sheet metal by a stamping operation, which is much less costly than either the aluminum castings heretofore used, or the fabrication of an ordinary thimble.

The construction herein shown is particularly well adapted for use in connection with aluminum sheet, due to the reinforcing effect exerted by the web or central portions of the two plates.

Although only preferred embodiments of this

invention have been shown and described herein, it will be apparent that various modifications and changes may be effected in the constructions shown without departing from the spirit of this invention as defined in the appended claim.

5 We claim:

A thimble for dead ending aluminum wire comprising two aluminum plates having contacting central portions, and offset marginal portions which cooperate with each other to form a curved groove, a series of rivets passing through said central portions and securing them to each other, said rivets being spaced adjacent the bottom of the groove formed by said marginal portions, and said plates being shaped so that each of said marginal portions is provided with an extension, said extensions being oppositely disposed and providing supporting arms for said thimble.
